UNITED STATES PATENT OFFICE.

HANNAH CHISHOLM FRASER, OF BOURNEMOUTH, ENGLAND.

STOCKING AND LIKE GARMENT AND TO ATTACHMENTS THEREFOR.

Application filed October 27, 1920. Serial No. 419,980.

To all whom it may concern:

Be it known that HANNAH CHISHOLM FRASER, of Bournemouth, Hampshire, England, a subject of the King of Great Britain, hath invented certain new and useful Improvements in Stockings and like Garments and to Attachments Therefor, of which the following is a specification.

This invention has reference to stockings and like garments and to attachments therefor, for use with suspenders or like supporting means.

I have found that the pull of a suspender on a stocking is more evenly and better distributed around the stocking if the points at which the suspender attachment is secured to the stocking do not coincide with the centre of the loops on the attachment and that, as regards an attachment formed by securing a length of fabric to a stocking so as to form a continuous band with spaced loops, the stitching which fastens the attachment to the stocking should enclose small areas each disposed intermediate the loops. In this way, the pulling strain on the stocking is properly distributed so as to take full advantage of the elasticity of the stocking fabric without damaging the same, at the same time giving the stocking a very neat appearance. The method of attaching the length of fabric to the stocking, i. e. by spacing the points of attachment intermediate the supporting loops and securing the said attachment to the stocking at localized points only, has the advantage that full benefit may be taken of the elasticity of the material when the stocking is stretched laterally, for example, when it is being pulled over the knee of the wearer. It will be obvious that if the stocking is pulled in opposite directions at two of said localized points of attachment, the material between the latter will be able to stretch owing to the free length of the loop of fabric disposed intermediate the points of attachment, which permits of such stretching, whereas if the attachment were secured to the stocking by a continuous chain of stitches such stretching would be impossible.

According to this invention, I provide a new article of manufacture for use with stockings and similar garments and suspenders, comprising a length of fabric crossed to form a loop and secured at the crossing and enlarged tabs formed on the

fabric spaced from each other and forming the only points of connection between the said length of fabric and the stocking or similar garment, so that the supporting pull is spaced around the circumference of the stocking or similar garment being exerted diagonally thereon and lateral stretching of the material of the said stocking or similar garment being permitted, whilst the flexibility of the said material is preserved. The effect of such pulling strain is to draw the points of attachment of the loop or loops with the stocking closer together and thus take advantage of the elasticity of the material and avoid unduly stretching the garment or pulling it out of shape.

The loop or loops is or are secured at its lower ends or portions to the stocking or other garment and the looped portion or portions extends or extend upwardly therefrom.

Preferably the loop or loops is or are formed of a fabric which is flexible lengthwise, such as a knitted or like fabric, although other fabrics may be used if desired.

The loop or loops are provided or formed with enlarged or suitably shaped portions which are attached by stitches to the stocking or other garment. The loop or loops may be connected to a band or garter adapted to be attached to the stocking or the like, or the latter may be knitted or otherwise woven with a thickened portion around that part to which the loop or loops is or are attached.

The invention is further described in connection with the accompanying drawings, wherein examples of various constructions are illustrated, and in these drawings, Fig. 1 shews the upper end of a stocking provided with a looped means for the connection of a suspender therewith, Fig. 2 illustrates the looped means connected with a suspender and the effect of such connection, Fig. 3 illustrates a looped connecting means ready for attachment to a stocking, Fig. 4 is an illustration of a looped connecting means provided in conjunction with a band or garter, part of which is illustrated, adapted for attachment to the stocking, Fig. 5 shews the upper end of a stocking reinforced or fitted with a garter or band at that part to which the looped connecting means is attached, and Fig. 6 is an illustration of a modified form of looping means.

2

Referring to the construction of looped connecting means shewn in Figs. 1, 2 and 3, this may be formed of any suitable woven or other fabric or material, preferably of 5 knitted, plaited or like fabric with upwardly projecting loops a produced by crossing the fabric or material between the points or tabs b at which the looped connecting means is secured to the stocking or the like. These 10 points or tabs b may be produced in any suitable manner, such as by forming enlargements in the said fabric during its production, or by coiling or looping the same upon itself. The crossing parts c of the 15 fabric or material are secured together to maintain the upwardly projecting parts as loops a . In Fig. 1 the means is shewn attached to the upper end d of a stocking, while in Fig. 3 the connecting means is 20 shewn by itself ready for attachment to the garment.

Fig. 2 illustrates the means in use, one of the loops being connected with a suspender. In this view it will be seen that 25 the elasticity of the material or fabric of the stocking comes into use in the support of the garment, the strain on the garment, especially during walking, being taken up by the material or fabric, such strain being 30 distributed laterally and around the part to which the connecting means is attached, thus avoiding undue strain or any damage to the garment and at the same time imparting a 35 sense of comfort hitherto unknown with suspender attachments.

The attachment of the means to the stocking or the like may be effected by sewing or in any other suitable manner, such sewing or its equivalent securing the lower parts 40 of the loops, or the tabs b , to the stocking.

The alternative construction shewn in Fig. 4 comprises a loop connecting means formed by crossing the material or fabric at a series of parts as denoted by c and securing the crossing parts together. By the provision of a series of loops a number of points of connection are provided for the suspender. In this alternative construction is also illustrated a part of a band or garter 50 f of knitted material or fabric to which the looped connecting means is attached at the points b .

The band and the looped connection may be formed of any suitable fabric or material, but knitted or like fabric is preferred, although, if desired, elastic, or similar fabric or material may be employed. It is found in practice that the knitted or like fabric is very adaptable for the looped connecting 60 means and possesses the desired elasticity or flexibility suitable for the purpose.

A further alternative is illustrated in Fig. 5 wherein the stocking is reinforced or strengthened as at g around the part to 65 which the connecting means is attached.

In this figure the upwardly projecting loops, one on each side, are shewn at c and c' as crossed, while the middle upwardly projecting loop a' is shewn as not crossed. Enlargements or tabs b are provided for the 70 attachment of the loops to the stocking or part to be attached thereto. This construction is more particularly adapted for stockings and like garments of a thin or light weight character, and may be employed in 75 connection with medium or thick stockings, although the latter will be generally strong enough for the attachment of the connecting means without any reinforcing. Where desired, the garment may be reinforced or 80 strengthened in any desired manner, or the loops or looped connecting means may be provided or formed with enlargements or tabs or their equivalent for the secure attachment thereof and for strengthening that 85 or those part or parts of the stocking to which the means is attached.

The modified construction shewn in Fig. 6 comprises a looped connecting means formed of cord or similar material knotted at the points c' to form a series of loops a'' as shewn. The ends of the cord are 90 preferably enlarged as at b for obtaining a secure and distributed attachment to the stocking.

As an alternative means for securing the looped connecting means to the stocking, the means may be provided on a piece of knitted or like fabric adapted to form or serve as the top of a stocking. Such a top 100 or its equivalent may be secured in position in any suitable manner and may be substituted for a damaged part removed from the stocking.

The improved means serves not only to 105 provide for greater comfort to the wearer or user of suspenders, but also enables stockings of a single thickness throughout, that is, with a so-called single hem to be made use of with absolute comfort and an entire absence of damage during use, thus considerably economizing in the initial cost, and at 110 the same time ensuring an attractive appearance of the stocking throughout the life thereof.

The construction shewn in Fig. 5 applies also to a stocking top d formed with either a reinforced part g or having attached to it a band or garter f , and it will be obvious that such top d may be formed either separate and distinct from the stocking and adapted for attachment thereto, or constitute the upper end of a stocking formed with either a so-called "single" or "double" 115 top.

What is claimed is:—

A new article of manufacture for use with stockings or similar garments and suspenders, comprising a length of fabric crossed to form a loop and secured at the crossing 120

and enlarged tabs, formed on the fabric, spaced from each other and forming the only points of connection between the said length of fabric and the stocking or similar garment, so that the supporting pull is spaced around the circumference of the stocking or similar garment being exerted diagonally thereon and lateral stretching of the material of the said stocking or similar garment being permitted whilst the flexibility of the ~~10~~ said material is preserved.

In testimony whereof I affix my signature in presence of two witnesses.

HANNAH CHISHOLM FRASER.
